UNITED STATES PATENT OFFICE.

SAMUEL BUCHSBAUM, OF CHICAGO, ILLINOIS.

BELT-BUCKLE.

1,340,821.

Specification of Letters Patent. Patented May 18, 1920.

Application filed May 8, 1919. Serial No. 295,595.

To all whom it may concern:

Be it known that I, SAMUEL BUCHSBAUM, a citizen of the United States, residing at Chicago, in the county of Cook and State of Illinois, have invented a certain new and useful Improvement in Belt-Buckles, of which the following is a full, clear, concise, and exact description, reference being had to the accompanying drawings, forming a part of this specification.

My invention relates to belt buckles and has for its object the provision of a new and improved clasp or holding means for retaining the free tongue of the belt in any desired position. My invention has for its prime object the construction of a clasp of this nature, which in its simplest form consists of a single piece of metal punched and formed into shape to fulfil all of the requirements of a device of this character.

The clasp structure in its simplest form consists of a movable clasp element coöperating with the buckle base plate. The movable clasp element is movably carried by the base plate and has means for preventing its dislodgment from its permanent location.

I will describe one form which my invention will take, more in detail, by referring to the accompanying drawing, in which—

Figure 1 is a perspective view of a belt buckle constructed in accordance with my invention;

Fig. 2 is a side view thereof;

Fig. 3 is a bottom view thereof;

Fig. 4 is a sectional view on line 4—4 of Fig. 1; and

Fig. 5 is a perspective view of the adjustable clasp element.

Fig. 6 is a fragmentary sectional view illustrating a modified form of my invention, and

Fig. 7 is a perspective view of the modified form of adjustable clasp element shown in Fig. 6.

By referring more particularly to the figures, I show a buckle base plate 10 having the front wall 11 and two rearwardly extending flanges or side walls 12. At the left hand extremity of the base plate 10 there is a pivotally carried clamping structure 14 which is designed permanently to clamp in position the extremity 15 of the belt. The free belt tongue 16 is then held in position in any desired portion of its length through the agency of my improved structure as will presently appear. The clamping structure

14 includes a pivotally mounted element 17 having the pins 18 by virtue of which it is pivotally carried in the side walls 12 of the base plate 10. This element 14 carries the clamping cam 19 for permanently locking the belt extremity 15 to the element 14. The belt extremity 15 is thus pivotally supported in the buckle base plate 10.

My improved clasp structure for holding the belt tongue 16 consists of the movable clasp element 20 which coöperates for clasp purposes with the base plate 10. The movable clasp element includes a bridge structure 21 having at its extremities projections 22 by virtue of which the clasp element is slidable in slots 23 formed in the side walls 12 of the base plate. The side walls 12 are bent into their present position after the bridge structure 21 with its projections 22 has been placed in its allotted position. My improved clasp element has backwardly extending shoes or guides 24, 24, at the top and bottom thereof, which prevent a swinging movement of the said clasp element in the plane of the slot 23. These shoes or guides 24 thus prevent dislocation of this movable clasp element relative to the belt base plate 10. The structure, however, is such that the movable clasp element 20 may slide longitudinally of the slots 23. It will be noted that the slots 23 slope forwardly toward the front wall 11 of the base plate 10 so that a movement of the movable clasp element from left to right will bring the inner edge of the bridge structure 21 closer to the wall 11. In this manner the belt tongue 16 is locked in position between the front edge 13 of the movable clasp element 20 and the front wall 11 of the base plate 10. When it is desired to withdraw the tongue 16 it is pushed to the left and the projections 22 held by the fingers, whereupon the belt tongue can be withdrawn. It will be also noted that the backwardly extending shoes 24 form effective means to hold the front edge 13 of the movable clasp element 20 in its locking position to prevent any large amount of rotation of said movable clasp element about the axis of the projections 22. It will also be seen that the movable clasp element 20 can be formed from a single blank of metal, the parts being bent into their appropriate positions, thus providing a very simple device of this nature.

Referring to Figs. 6 and 7, I show a modi-

fied structure 20^a of my improved clasp element provided with a bridge structure 21^a having sidewardly extending shoes or guides 24^a. These shoes 24^a serve to prevent dislocation of the clasp element relative to the base plate.

While I have herein shown and particularly described several forms which my invention may take, what I claim as new and 10 desire to secure by Letters Patent is:—

1. A device of the character described comprising a base plate having front and side walls, said side walls having inclined slots, and a movable clasp element having 15 flattened projections slidably mounted in said slots, and adapted to clamp the free extremity of a belt tongue against said front wall, said flattened projections and slots permitting only a limited swinging movement 20 of said clasp relatively to the plate.

2. A device of the character described comprising a base plate having front and side walls, said side walls having inclined guides, and a movable clasp element pivotally and slidably mounted in said guides, and having a limited swinging movement 25 relatively to the plate and adapted to clamp the free extremity of a belt tongue against said front wall, said clasp element engaging 30 the belt at opposite sides of its pivot.

3. A device of the character described comprising a base plate having front and side walls, said side walls having guides, and a movable V-shaped clasp element slidably mounted in said guides, and adapted 35 to engage the belt at a plurality of points to clamp the free extremity of the belt tongue against said front wall.

4. A device of the character described 40 comprising a base plate having front and side walls, said side walls having inclined slots, and a movable clasp element slidably mounted in said slots and having a limited pivotal movement therein, and adapted to 45 clamp the free extremity of a belt tongue against said front wall, said movable clasp element having auxiliary guide means coöperating with said base plate for maintaining 50 said clasp element in proper relationship to its slots.

5. A device of the character described comprising a base plate having front and side walls, said side walls having inclined guides, and a movable clasp element slidably mounted in said guides, and having a limited pivotal movement therein, and adapted to 55 clamp the free extremity of a belt tongue against said front wall, said movable clasp

element having auxiliary guide means coöperating with said base plate for maintaining 60 said clasp element in proper relationship to its guides.

6. A device of the character described comprising a base plate having front and side walls, said side walls having guides, and a movable clasp element slidably mounted in said guides, and adapted to clamp the free extremity of a belt tongue against said wall, said movable clasp element having auxiliary guide means coöperating with said base plate for maintaining 70 said clasp element in proper relationship to its guides, and a second clamp element pivoted on said plate and adapted to have the other end of the belt secured thereto.

7. A device of the character described comprising a base plate having front and side walls, said side walls having guides, and a movable clasp element slidably mounted in said guides, and adapted to clamp the free extremity of a belt tongue against said wall, said movable clasp element having 80 backwardly extending shoes coöperating with said base plate for maintaining said clasp element in proper relationship to its guides, and a second clamp element pivoted on said plate and adapted to have the other 85 end of the belt secured thereto.

8. A device of the character described comprising a base plate having front and side walls, said side walls having guides, and a movable clasp element made of a single blank of material slidably mounted in said guides, and having a limited pivotal movement therein and adapted to clamp the free extremity of a belt tongue against said wall, said movable clasp element having 90 backwardly extending shoes coöperating with said base plate for maintaining said clasp element in proper relationship to its 95 guides.

9. A device of the character described comprising a base plate having front and side walls, said side walls having guides, and a movable clasp element made of a single blank of material slidably mounted in said 105 guides, and adapted to clamp the free extremity of a belt tongue against said wall, said movable clasp element having a rearwardly extending shoe at the top and bottom 110 thereof coöperating with the side walls of said base plate for maintaining said clasp element in proper relationship to its guides.

In witness whereof, I hereunto subscribe my name this 6th day of May, A. D. 1919.

SAMUEL BUCHSBAUM.
